United States Patent Office.

WILLIAM SMITH, OF CICERO, INDIANA.

Letters Patent No. 99,963, dated February 15, 1870.

IMPROVEMENT IN HOT-AIR FURNACES.

The Schedule referred to in these Letters Patent and making part of the same.

To all whom it may concern:

Be it known that I, WILLIAM SMITH, of Cicero, in the county of Hamilton, and State of Indiana, have invented a new and valuable improvement in Hot-Air Motors; and I do hereby declare that the following is a full, clear, and exact description of the construction and operation of the same, reference being had to the annexed drawings making a part of this specification, and to the letters and figures of reference marked thereon.

Figure 1 of the drawings is a representation of a vertical central section of my invention.

Figure 2 is a representation of a horizontal section of the same.

My invention relates to means for utilizing the upward force of heated air, and consists mainly in inclosing a suitably-constructed wind-wheel in a case supplied with air at the bottom, and provided with a furnace to heat the same and increase its ascension-force.

The letter A of the drawings designates the upright cylindrical casing, of indefinite length. Within this cylinder is the wind-wheel, consisting of a perpendicular shaft, a, and the oblique semicircular wings B B attached thereto. These wings B B are arranged at equal distances apart on the shaft a in sets of three, each plate or wing being inclined to the perpendicular at an angle of about forty-five degrees.

The casing A may be made of any desired length, and this will determine the number of sets of wings employed.

The shaft a is arranged to have its lower bearing in a step or on a stud-pivot, as at z, and its upper bearing in a cross-piece, c.

Should a case of extreme length be employed, supplementary cross-pieces may be employed at different distances to support the shaft.

To the top of the case A, I usually attach an ordinary chimney or stack, which may be surrounded by any of the draught-creating ventilators in common use.

At the bottom of the case A is arranged a number of air-ducts, D D, sufficient for the supply of air.

A flue, F, leading to a furnace is also connected with the lower portion of the case A, whereby the ascending air is heated.

Connected with the ducts D D are the regulating dampers h h, whereby the velocity of the wheel is easily controlled.

A pulley, S, is attached to the shaft a under the case A, and by means of a belt therefrom the power of the wheel is communicated to machinery.

What I claim as my invention, and desire to secure by Letters Patent, is—

In combination with the upright cylindrical case A connected with a furnace, and provided with the air-ducts d d having dampers h h, the wind-wheel herein described, having upright shaft a and inclined blades B B, all constructed and arranged to operate as specified.

In testimony that I claim the above, I have hereunto subscribed my name in the presence of two witnesses.

WILLIAM SMITH.
